UNITED STATES PATENT OFFICE.

ALFONS H. NEULAND, OF NEW YORK, N. Y.

DYNAMO-ELECTRIC MACHINE.

1,223,096.

Specification of Letters Patent. Patented Apr. 17, 1917.

Original application filed January 19, 1914, Serial No. 812,908. Divided and this application filed March 30, 1915. Serial No. 18,009.

To all whom it may concern:

Be it known that I, ALFONS H. NEULAND, a subject of the Czar of Russia, residing at New York city, in the borough of Manhattan and State of New York, have invented certain new and useful Improvements in Dynamo-Electric Machines, of which the following is a full, clear, and exact description.

- 10 My invention relates to dynamo-electric machines, and particularly to such machines of the type shown in my co-pending application, Serial Number 812,908, filed January 19, 1914, of which this is a division. In my 15 said original application, a generator is disclosed in which a current is generated in a coil through the shifting of the generating flux alternately from one part to the other of two-part pole pieces by a rotating toothed 20 inductor which coöperates with teeth on the pole pieces.

An object of my present invention is to provide simple and convenient means for properly spacing and rigidly supporting 25 the field parts of such a machine. Another object is to so support the parts as to prevent the generation by the shifting or varying flux of currents in the closed circuits formed partly by the supporting members, 30 which would choke back the flux. Other objects are convenience in assembling the parts, simplicity and compactness of construction, and reliability in operation. Still other objects and advantages of my invention 35 will appear from the following description.

In accordance with my invention the supporting members, which form parts of closed circuits, are so arranged relative to the magnets and pole-parts that the flux through 40 each closed circuit is constant, whereby the supports do not interfere with the shifting flux. Preferably the pole pieces are supported at their ends and at a point midway 45 of their ends, their middle support also serving to support the magnets. The middle support is preferably a rib integral with the frame or casing, which also serves to space the magnet sections, and the end supports 50 may be lugs or arms also integral with the casing and each lug serving as a common support for two adjacent pole pieces, though bolts or other suitable devices attached to the frame may be employed for the supports.

55 My invention also includes various other

features of construction, arrangements and combinations of parts, as will hereinafter more fully appear.

I shall now describe the embodiment of my invention illustrated in the accompanying drawings and shall thereafter point out my invention in claims.

Figure 1 is a central axial section of a generator embodying my invention; and

Fig. 2 is a transverse section of the same.

The illustrated magneto has a suitable cylindrical frame or casing 1 of non-magnetic material such as aluminum, closed on one face by an integral wall 1^a, and a removable wall 1^b being provided for the other face. The cylindrical wall is provided on diametrically opposed sides with a plurality of internal longitudinal ribs, shown as two, and marked, respectively, 20 and 21, and there is also a corresponding number of outstanding lugs or arms 22 and 23 extending parallel with the axis of the casing and integral with the wall 1^a and spaced somewhat from the inner periphery of the cylindrical wall of the casing. The permanent magnet is composed of a corresponding number of arcuate parts or sections 2 and 2^a fitting within the casing and spaced by the ribs 20 and 21, the magnet sections being laminated.

These magnet sections 2 and 2^a are arranged with their north poles and south poles adjacent, forming in the construction shown one permanent north pole and one permanent south pole, as indicated by the letters N and S. These poles are provided with laminated pole pieces of general arcuate shape which are non-integral or separate members and arranged internally of the magnets, their two ends abutting against the lugs or arms 22 and 23, and their centers contacting against the respective ribs 21 and 22 and adjacent ends of the magnet sections. In the form shown, the arms or lugs 22 and 23 are of general T-shape in cross section and have their heads extending oppositely over the adjacent ends of the pole pieces. The laminated magnets and pole pieces are thus rigidly supported and locked in the frame and securely held in place against lateral or circumferential displacement.

The pole pieces are provided with central coil-receiving slots 3 and 3', respectively, and the halves or sections on opposite sides of these slots form pole-parts or divisions S', S^a, N' and N^a, respectively, the pole-

parts S' and N² being on one side of the coil 5, and the pole-parts N' and S² being on the opposite side of the coil. The induced coil 5 is arranged within the slots 3 and 3', and 5 extends between the poles longitudinally of the casing and surrounding the inductor.

The inner faces of the pole-parts are arranged in a circle and are provided with similar teeth 6^a, 6^b, 7^a and 7^b, respectively, 10 arranged parallel to each other and to the axis of the casing. The teeth on each section are of the same pitch and the two adjacent teeth on the opposite sides of each of the slots 3 and 3' are so spaced apart that 15 the teeth on one pole-part are offset from the teeth on the other pole-part of the same polarity a distance equal to one-half a tooth pitch.

Mounted axially in the casing and rotatable between the pole pieces is an inductor 8 formed of a plurality of annular laminated plates, preferably of steel, mounted upon a drum 9 which has a hub portion fixed on the shaft 10 of the inductor, which is 25 driven by the engine shaft 10' in any usual or suitable way, as by gearing, as shown. The shaft 10 bears in the sleeve 11 which is secured within an inwardly-projecting hub 12 integral with the front of the casing. 30 The inductor is provided with teeth 8^a similar and parallel to those on the pole pieces, and of a similar pitch, the diameter of the inductor being such that the ends of its teeth rotate in close proximity to the inner 35 ends of the teeth on the pole pieces. Due to the offsetting of the teeth on one pole-part of each polarity a distance equal to one-half a tooth pitch, relative to those on the other pole-part of the same polarity, it is evident 40 that, as the inductor rotates, its teeth alternately are alined with those on pole-parts of opposite polarity on opposite sides of the coil, that is, in one position its teeth are alined with teeth on pole-parts 6^a and 7^a, 45 and an angular movement of the inductor for one-half a tooth pitch causes its teeth to aline with those on pole-parts 6^b and 7^b, and it is evident that the teeth of the inductor are staggered in these respective 50 positions with the teeth with which they are not alined. Since the magnetic flux will assume the path of least reluctance, it is evident that the flux is therefore reversed through the coil for each angular movement 55 of the inductor for a distance of one tooth pitch, and that for each complete rotation of the inductor twice as many impulses are produced in the coil as there are teeth on the inductor; in this way a current of sufficiently high frequency for lighting purposes 60 is generated at low speeds of the inductor.

It will be noted that the supports are arranged so that wherever they form part of several closed circuits, the flux through such 65 circuits is constant; for instance the flux is

constant through the electric circuit formed by the middle support, one of the end supports and the laminations, since the middle support is so located that the flux in shifting from one pole-part to the other takes its 70 path through the section of the pole piece between the coil-receiving slot and the middle support, and the flux through the circuit formed by the two end supports and the laminations is also constant, being equal to 75 the flux produced by all the magnets. Rotation of the inductor does not cause the flux to vary through this circuit but only changes the position of the flux with respect thereto.

The supporting means for the magnet sections and pole pieces are extremely simple of construction and permit the parts to be conveniently assembled, while holding them 80 rigidly in their proper positions.

It is obvious that various modifications 85 may be made in the construction shown in the drawings and above particularly described within the principle and scope of my invention.

I claim:—

1. In a dynamo electric machine, means for producing a magnetic flux, a plurality of toothed two-part pole pieces, one for each pole of the field, a toothed rotative inductor coöperative with the teeth on the pole 95 pieces to alternately shift the flux from one pole-part to the other of the respective pole pieces, and for each pole piece supporting members so arranged that the flux passing between the supporting members remains 100 constant, whereby the flux is permitted to shift from one pole-part to the other without interference.

2. In a dynamo-electric machine, means for producing a magnetic flux, a plurality of toothed pole pieces, one for each pole of the field and each pole piece being provided with a coil-receiving slot dividing the pole piece into two pole-parts, a toothed rotative inductor coöperative with the teeth on the 105 pole pieces to alternately shift the flux from one pole-part to the other of the respective pole pieces, and a supporting member for each pole piece engaging the pole piece at a point adjacent to the coil-receiving slot 110 and on the side opposite the inductor.

3. In a dynamo-electric machine, means for producing a magnetic flux, a plurality of toothed pole pieces, one for each pole of the field and each pole piece being provided 115 with a coil-receiving slot dividing the pole piece into two pole-parts, a toothed rotative inductor coöperative with the teeth on the pole pieces to alternately shift the flux from one pole-part to the other of the respective 120 pole pieces, and supporting and spacing means for each of the pole pieces comprising two end supports and a middle support, the middle support engaging the pole piece at a point adjacent the coil-receiving slot and on 125 130

the side opposite the inductor, whereby the supports permit the flux to shift from one pole-part to the other without interference.

4. In a dynamo electric machine, means for producing a magnetic flux, a plurality of toothed two-part pole pieces, one for each pole of the field, a toothed rotative inductor coöperative with the teeth on the pole pieces to alternately shift the flux from one pole-part to the other of the respective pole pieces, an induced winding axially surrounding the inductor, and supporting means for the pole pieces arranged to permit the flux to shift from one pole part to the other without interference.

5. In a dynamo-electric machine, in combination with the frame, a plurality of circumferentially arranged magnets, a plurality of toothed two-part pole pieces, one for each pole of the field, a toothed rotative inductor coöperative with the teeth on the pole pieces to alternately shift the flux from one pole-part to the other of the respective pole pieces, and a plurality of magnet spacing members carried by the frame and arranged between the adjacent ends of the respective magnets and each member engaging and supporting the respective pole piece.

6. In a dynamo-electric machine, in combination with the frame, a plurality of circumferentially arranged magnets, a plurality of toothed pole pieces, one for each pole of the field and each pole piece being provided with a coil-receiving slot dividing the pole piece into two pole-parts, a toothed rotative inductor coöperative with the teeth on the pole piece to alternately shift the flux from one pole-part to the other of the respective pole pieces, a plurality of magnet spacing members carried by the frame and

arranged between the adjacent ends of the respective magnets and each member engaging the respective pole piece adjacent the coil-receiving slot and on the side opposite the inductor and supporting the pole piece 45 at this point, and a corresponding number of end supporting members for the pole pieces carried by the frame and each end supporting member engaging and supporting the two adjacent ends of two adjacent 50 pole pieces, whereby the supports permit the flux to shift from one pole-part to the other without interference.

7. In a magneto generator, a frame of non-magnetic material provided with a plurality of magnet-spacing ribs on its inner periphery and a corresponding number of outstanding lugs or arms spaced from the periphery and substantially parallel with the axis of the casing, magnet sections fitting 60 within the casing and extending between and spaced by the ribs and arranged with the adjacent ends of the successive magnet sections of the same polarity, toothed two-part pole pieces having their ends bearing against and supported by two consecutive outstanding lugs or arms and supported midway of their ends by the intervening ribs, one pole piece making magnetic contact with the two adjacent ends of the two magnet sections, and a toothed rotative inductor coöperative 70 with the teeth on the pole pieces to alternately shift the flux from one pole-part to the other of the respective pole pieces.

In witness whereof, I subscribe my signature, in the presence of two witnesses.

ALFONS H. NEULAND.
